UNITED STATES PATENT OFFICE

2,410,484

SLIDING CAR DOOR

Frank Ditchfield, Cleveland, Ohio, assignor to The Youngstown Steel Door Company, Cleveland, Ohio, a corporation of Ohio

Application August 29, 1940, Serial No. 354,709

9 Claims. (Cl. 20—26)

1

This invention relates to sliding railway car doors and is directed more particularly to the construction of the rear portions of said doors by means of which the entry of rain, snow, dust, cinders and the like into the car is prevented.

It is an object of this invention to provide sliding doors for railway cars which shall incorporate flexible weatherstrips.

A further object is to provide sliding doors embodying flexible weatherstrips disposed so as to be protected by adjacent portions of said doors.

A further object is to provide sliding doors for railway house cars embodying flexible weatherstrips arranged to cooperate with members of the side walls of said cars to afford effective seals.

A further object is to provide sliding doors embodying non-metallic angular weatherstrips wherein said doors are so constructed that inexpensive flat strips of flexible non-metallic material may be utilized to provide the angular weatherstrips without pre-forming said strips.

A further object is to provide sliding doors embodying non-metallic flexible weatherstrips adapted to engage members of the side walls of said cars to provide seals, said weatherstrips being characterized by their ability to adjust themselves to the vibrations of the doors and thereby eliminate sliding friction between them and the side wall members which they engage.

A further object is to provide sliding doors for railway house cars which shall incorporate weatherstrips in such manner as to secure interchangeability of said doors with similar doors not provided with weatherstrips.

Other objects of the invention will become clear as the description thereof proceeds.

In the drawing forming part of this specification:

Fig. 1 is a partial elevation of the rear portion of a sliding door embodying the invention.

Fig. 2 is a horizontal section taken on line 2—2 of Fig. 1.

Fig. 3 is a horizontal section taken on line 3—3 of Fig. 1.

Fig. 4 is a horizontal section taken on line 4—4 of Fig. 1.

Fig. 5 is a horizontal section illustrating the invention utilized at the meeting edges of double sliding doors.

The invention is shown applied to a sliding metallic door 10, utilized upon a freight car of the house type. The metallic door illustrated embodies a metallic panel 11, preferably formed with horizontal corrugations 12, which at their rear edge merge into an outwardly offset portion

2

of the panel in the form of a vertical corrugation 13. The vertical corrugation 13 is spanned by a vertically extending plate 14 secured as by riveting to the metallic panel 11 on opposite sides of the vertical corrugation as indicated at 15 and 16. The rivets indicated at 16, which fasten the vertically extending plate 14 to the metallic panel 11, are utilized as well to secure a substantially Z-shaped sealing strip 17 and a reinforcing angle 18 to the marginal portion of the door lying to the rear of the vertical corrugation. The sealing strip 17 is disposed upon the plate 14, while one leg of the angle 18 is disposed upon the panel 11.

15 The upper horizontal margin of the door is reinforced by an angle member 19 extending substantially the width of the door and having the leg 20 arranged vertically and fastened to the upper margin. The other leg 21 of the angle member 19 is arranged horizontally and extends inwardly.

20 The lower horizontal margin of the door is reinforced by an angle member 22, the vertical leg 23 of which is disposed between and secured 25 to the vertically extending plate 14 of the metallic panel 11. The horizontally disposed leg 24 of said reinforcing angle extends outwardly.

25 The sealing strip 17 carried by the door is adapted to cooperate with a spark strip 25 fastened to the outwardly extending leg 26 of an angle member 27, which in turn is secured to the door post 28. This cooperation satisfactorily prevents sparks and large particles of foreign matter from entering the car.

30 To provide an effective weather seal which will efficiently exclude rain, snow, dust, cinders and the like without impairing the interchangeability of the door, the vertically extending plate 14 is provided with an inwardly opening recess 29.

35 Within this recess one flange 30 of a rubber, or rubber and fabric weatherstrip 31, is secured by means of a flat metallic plate 32 and rivets 33. As indicated by the dotted lines the flange 34 of the weatherstrip 31 extends inwardly and is so positioned as to be protected by the forwardly extending flange 35 of the sealing strip 17. The disposition of the inwardly extending flange 34 of the weatherstrip 31 insures engagement between this flange and the spark strip 25 when

40 the door is in closed position. The inherent resiliency of the flange 34 and the engagement thereof with the spark strip provide an effective seal to exclude rain, snow, dust, cinders and the like. It is to be observed, moreover, that this seal is secured by the instant invention without

the necessity of compressing the weatherstrip, and that mere flexing or bending of the strip is sufficient.

It is desirable that the weatherstrip extend substantially the full height of the door. To this end the metallic panel 11 and the plate 14 are removed above the vertical corrugation beginning from substantially the lower edge of the vertical flange 20 of the angle member 19 to the upper edge of the panel and the plate. To close any opening which might have been made, the lower edge of the vertical flange 20 is welded to the metallic panel 11, as indicated in Fig. 1 of the drawing. As a result of the removal of the indicated portions of the panel and plate, the flange 30 of the weatherstrip 31 can be extended upwardly to the underside of the horizontal leg 21 of the angle member 19. It will be observed that this flange of the weatherstrip lies against the inner face of the vertical leg 20 to which it is secured by the flat plate 32 and the rivets 33.

To secure extension of the weatherstrip 31 to substantially the lower edge of the door, the vertical leg 23 of the lower reinforcing angle 22, which lies below the vertical corrugation 13, is removed, as indicated at 38, while the outwardly extending horizontal leg 24 continues to the end of the angle member 22, as indicated at 39. To close any opening which might result from the removal of the indicated portion of the vertical leg 23, the angle member 22 is welded, as indicated at 40 and 41. By reason of this construction the continuity of the metallic panel 11 is not disturbed, see Fig. 4, and the plate 14 and the weatherstrip 31 extend continuously substantially to the bottom edge of the door. Space for the recessed portion 29 of plate 14 is provided by the removal of the indicated portion of the vertical leg 23 of the lower reinforcing angle 22 as more clearly shown in Fig. 4 of the drawing. The weatherstrip 31, accordingly, is utilized to secure a seal for the entire height of the door.

While the weatherstrip 31 appears angular in section when applied to the door 10, the invention nevertheless contemplates the use of a flat strip. When the flat strip is secured within the inwardly opening recess 29, as described hereinabove, it is caused to bear against a shoulder, or abutment, 42 formed by the recess in the plate 14. The flat strip is thereby turned inwardly to the position indicated by the dotted lines in Fig. 2 of the drawing, thereby forming the inwardly extending flange 34 of the weatherstrip.

Preference has been shown herein for a non-metallic weatherstrip formed of rubber, or rubber and fabric. It is to be understood that the instant invention is not limited to these materials, but that a flexible weatherstrip of any other material suitable for the purpose of the invention may be utilized. It will be clear, moreover, that the invention is not limited to the particular structure of the door illustrated and that it may be utilized with other types of door as well.

The instant invention is applicable as well to the main and auxiliary sliding doors of a double door construction. The main door is designated by the reference numeral 43 in Fig. 5 of the drawing and the auxiliary door by the reference numeral 44. Secured to the front vertical margin of the auxiliary door 44 is a post 45 which preferably is movable with the door. A stop 46 for limiting closing movement of the main door 43 is disposed between the auxiliary door and the auxiliary door post and is secured to the door by the same rivets fastening the post thereto. The

door stop 46 is provided with a readwardly extending flange 47 spaced from the post flange 48 through which the securing rivets extend.

The flange 48 of the auxiliary door post 45 is formed with an outwardly opening recess 49 beyond which the flange 48 is continued, as indicated at 50, to provide guide means for the main door 43. A flat weatherstrip 51 formed preferably of rubber, or rubber and fabric, is seated within the recess 49 and is fastened thereto by means of an angular plate 52 and rivets 53. As clearly indicated in Fig. 5 of the drawing the flat weatherstrip is caused to bear against the outer wall of the recess 49 so as to provide an outwardly extending flange 54 on said weatherstrip. The flange 54 extends into the space between the auxiliary door post 45 and the rearwardly directed flange 47 of the main door stop. In this position the flange 54 is engaged and flexed by the main door 43 in its final closing movement and establishes an effective seal therewith.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. A longitudinally sliding metallic door for railway house cars comprising a panel having a vertical outwardly extending corrugation adjacent to the rear edge thereof, a vertical plate extending across said corrugation and secured on opposite sides thereof to said panel, a vertical inwardly opening recess in said plate, an angle shaped flexible weatherstrip having one flange seated in said recess and the other flange extending inwardly and means securing said weatherstrip in said recess, said latter flange being adapted to engage a member extending from the wall of said car and to be flexed thereby during final longitudinal closing movement of said door, for the purpose set forth.

2. A longitudinally sliding metallic door for railway house cars embodying a member having a vertical inwardly opening recess inwardly of the rear edge of said door, a weatherstrip having a flange seated in said recess and a flexible flange extending inwardly beyond the inner plane of said door, and means securing said first mentioned flange of said weatherstrip in said recess, said flexible flange being adapted to engage a member extending from the wall of said car and to be flexed thereby during final longitudinal closing movement of said door, for the purpose set forth.

3. A sliding metallic door for railway house cars embodying a metallic sealing strip secured to said door, a flexible flanged weatherstrip and means securing said weatherstrip to said door, a flange of said weatherstrip extending inwardly beyond the inside of said door, said metallic sealing strip having a flange spaced inwardly of the inside of said door and overlying the inwardly extending flange of said weatherstrip for the purpose set forth.

4. In a double door construction for railway house cars a longitudinally sliding auxiliary door, a longitudinally sliding main door, a post secured to the front vertical margin of said auxiliary door, an angular stop member secured to the front vertical margin of said auxiliary door having a flange spaced laterally from said post and a flexible weatherstrip secured to said post

and having a flange extending into said space, said main door engaging and flexing said weatherstrip during final longitudinally closing movement, for the purpose set forth.

5. In a double door construction for railway house cars, a longitudinally sliding auxiliary door, a longitudinally sliding main door, a post secured to the front vertical margin of said auxiliary door having a flange arranged substantially parallel to said door, an angular stop member secured to the front vertical margin of said auxiliary door having a flange spaced from said post flange, said post flange having a recess and a flexible weatherstrip secured in said recess, a portion of said weatherstrip extending into said space, said main door engaging and flexing said weatherstrip during final longitudinally closing movement, for the purpose set forth.

6. A longitudinally sliding metallic door for railway house cars comprising a panel having a vertical outwardly extending corrugation adjacent to the rear edge thereof, a vertical plate extending across said corrugation and secured on opposite sides thereof to said panel, a reinforcing angle having a vertical leg secured to the inside of the lower margin of said panel, a vertical inwardly opening recess in said plate, an angle shaped flexible weatherstrip having one flange seated in said recess and the other flange extending inwardly, and means securing said weatherstrip in said recess, said vertical leg of said reinforcing angle adjacent to the rear edge of said door being removed to provide space for said recessed portion of said plate, said portion of said plate and said weatherstrips extending substantially to the lower edge of said door.

7. A longitudinally sliding metallic door for railway house cars comprising a panel having a vertical outwardly extending corrugation adjacent to the rear edge thereof, said corrugation terminating short of the upper edge of said panel, a vertical plate extending across said corrugation and secured on opposite sides thereof to said panel, a reinforcing angle having a vertical

leg secured to the outside of the upper margin of said panel, a vertical inwardly opening recess in said plate, an angle shaped flexible weatherstrip having one flange seated in said recess and the other flange extending inwardly and means securing said weatherstrip in said recess, said panel and said recessed portion of said plate above said corrugation being removed to provide space for said weatherstrip, said weatherstrip extending substantially to the upper edge of said door.

8. A longitudinally sliding metallic door for railway house cars comprising a panel having a vertical outwardly extending corrugation adjacent to the rear edge thereof, said corrugation terminating short of the upper edge of said panel, a vertical plate extending across said corrugation and secured on opposite sides thereof to said panel, a reinforcing angle having a vertical leg secured to the outside of the upper margin of said panel, a vertical inwardly opening recess in said plate, an angle shaped flexible weatherstrip having one flange seated in said recess and the other flange extending inwardly and means securing said weatherstrip in said recess, said panel and said recessed portion of said plate above said corrugation being removed to provide space for said weatherstrip, said weatherstrip extending substantially to the upper edge of said door, and means securing said first mentioned flange of said weatherstrip to said vertical leg of said reinforcing angle.

9. A longitudinally sliding metallic door for railway house cars having a vertical recess therein, a flexible weatherstrip seated in said recess, said weatherstrip having a flange, means securing said flange in said recess, said weatherstrip also having a flange extending freely beyond said recess, said latter flange being adapted to be engaged and freely bent by a member on said car associated with said door to form a seal between said car member and said latter flange, for the purpose set forth.

FRANK DITCHFIELD.
